SATTERLEE T. ARNOLD, OF IRVINGTON, NEW JERSEY, ASSIGNOR, BY MESNE ASSIGNMENTS, TO WILLIAM S. MILLS, OF BRIDGEPORT, CONNECTICUT

TRIMMING ATTACHMENT FOR LOOPING MACHINES

Application filed April 25, 1928. Serial No. 272,610.

My invention relates to new and useful improvements in trimming attachment for looping machines wherein sewing or looping mechanism is combined with an intermittent 5 or continuously revolving ring with radially projecting pins upon which the associated loops of the two portions of fabric to be united are carried.

The invention more particularly relates to 10 a trimming attachment for such machines whereby the superfluous projecting edges of the fabric may be uniformly removed, being cut, from the loops of a fabric when supported on the pins carried by the ring preparatory to the sewing or looping operations.

The primary object of the invention is to 15 generally improve upon trimming attachments of this class and to provide mechanism which is so constructed and operatively arranged as to produce closer and more uniform cutting in a manner to eliminate the work of ravelling as now required, and better adapt the machine to production of silk fabric.

The successive operations of the rotatable 20 table, of a looping machine of this type, which supports the work, serve to carry the knit fabrics forward to the trimming attachment.

These trimming mechanisms as heretofore provided in all instances include shearing 25 blades to shear off the superfluous edges of the fabric, and likewise contain guides for directing the edge of the material to be trimmed toward the cutter.

It is therefore an object of this invention 30 to provide a positively acting gripping mechanism whereby the projected superfluous material of the fabric is successively clamped, both against and independent of the ring carrying the impaling pins, so as to 35 provide means for gripping the material at two places and whereby the cutter can operate between the two said gripping points, to trim the fabric, thus forming a clean and close cut.

With the foregoing and other features in 40 view, it will appear as the description proceeds that the invention consists and resides in the arrangement and combination of parts and the detail in construction as hereinafter 45 described and claimed, it being understood

that changes in the precise embodiment of the invention herein disclosed may be made within the scope of what is claimed, without departing from the spirit of the invention.

Similar characters of reference will be 55 found to designate like or corresponding parts throughout the several figures of the accompanying drawings forming a part of this specification and upon which:

Fig. 1 shows a top plan view of a commercial type of looping machine having my improved trimming attachment applied thereto; 60

Fig. 2 shows upon an enlarged scale an inverted plan view of my improved trimming attachment detached from the loop machine. 65

Fig. 3 is a front elevation;

Fig. 4 is an end elevation as seen from the left of Fig. 3;

Fig. 5 is a somewhat similar end elevation, the guides being omitted; 70

Fig. 6 shows a detail of a rocker shaft and associated arms for operating the movable gripping jaw; and

Fig. 7 shows the associated gripping jaws 75 and cutter knife, in a closed position, also illustrated in Fig. 3.

In the accompanying drawings I have shown a top plan view of a portion of a looping machine of the revolving type and to 80 which my attachment is shown applied. This machine as illustrated includes a table 9 upon which the ring 10 is rotatably mounted and carries the impaling-pins 11 upon which the knitted fabric to be trimmed is supported. 85

The machine further includes an arm 12 which supports the table 9 and the reciprocatory and rotatable looping mechanism 13 operated by a shaft, not shown. This arm further supports a rotatable shaft 14 driven from the before mentioned shaft, not shown, and has its forward end portion journaled in a bearing 15 supported upon the table and provided with a socket 16 in which a flexible 90 shaft 17 of the trimming attachment is connected for its operation as shown attached in Fig. 1.

The trimming attachment includes a bracket 18 having a flanged base portion 19

that is attached to a table by means of a screw 20 and made adjustable thereon by adjusting screws 21, to properly set the bracket and position the operative parts of the trimmer, including the cutter, to insure accurate and effective functioning of the trimming mechanism. This bracket includes an outwardly disposed arm having an off-set extension forming a bearing 22 in which is mounted a shaft 23 having a collar 24 upon its outer end.

The before mentioned flexible shaft 17 is provided with a coupling 25 upon its outer end portion which fits upon and is secured to the end of the shaft 23 to drive the same from the before mentioned driven shaft 14. A cam element 26 is mounted upon this shaft and is provided on opposite sides with annular cam faces 27 and 28. The former serves to operate the clamping jaw 52 and the latter the cutter arm 30 bearing the cutting blade 31.

A pair of suitably shaped guides 32 and 33 properly spaced one with respect to the other are mounted upon the bracket and are positioned in proper relation to the path of movement of the pins of the ring to receive and guide the raw edge of the knit fabric carried upon the pins of the ring, between the clamping jaws preparatory to the cutting operations. The guide 33 includes an outwardly disposed rear end portion 34 to which an adjustable extension 35 is secured by means of a screw 36. This being the inner guide, see Fig. 1, it not only serves together with the other guide to gather in and align the edge of the fabric but by reason of the outwardly projected extensions 34 and 35 it serves to deflect the trimmed off particles of fabric out from the line of travel of the pins and fabric. This inner bracket member further includes a supporting arm 37 which is secured to the bracket 18 by means of screws 38, while the outer guide 32 is provided with an inwardly disposed looped arm 39 that is secured to the before mentioned arm 37 of the co-operating guide 33, by means of screws 40.

41 represents a depending jaw member which is formed upon the outer end portion of an arm 42 loosely mounted upon a rocker shaft 43 and susceptible of slight movement limited in one direction by a stop bracket 44 against which it is normally held by means of a spring 45, one end of which is secured to a pin 46 of said arm 42 and the other to a finger 47 secured to the frame by means of a screw 48.

The before mentioned rocker shaft 43, see Figs. 5 and 6, is journaled in the arm 18 of the bracket and serves to carry upon its lower end portion an arm 49 which bears a roll 50 that rides upon the annular cam face 27 of the cam element. A second arm 51 is mounted upon the upper end portion of the rocker shaft 43 and is provided upon its outer

edge portion with a depending jaw member 52 whose lower inturned gripping face aligns with the corresponding gripping face of the before mentioned jaw member 41 so that through the action of the cam the said movable gripping jaw 52 will be opened and closed against the co-acting normally stationary gripping member 41 in a way to clamp and hold the fabric therebetween during the cutting operation. This movable gripping member is normally held open and its roll arm retained against the cam face by means of a spring 53, one end of which is secured to the said roll arm 49 while the opposite end is attached to a pin of the lever 50 carrying the cutter blade.

A spring clamp 54 is adjustably attached to the side of the movable clamping jaw 52 by means of a screw 55. The inwardly disposed leg 56 of the clamp is arranged substantially parallel with the under face of the movable jaw and in spaced relation thereto. Its end serves to engage and disengage the periphery of the ring simultaneously with the clamping of the jaw so as to also grip the fabric below the line of movement of the knife and impaling pins, in its cutting operations.

The cutter lever 30 is pivotally mounted upon a stud 57 secured to the bracket 18. The forward end of this arm carries a clamping plate 58 and a screw 59 by means of which the cutting blade 31 is detachably secured to the forward end portion of the arm. The inwardly disposed leg of this arm carries a roll 60 that rides upon the cam face 28 and is actuated in a way to throw the lever and blade with each rotation of the shaft 23 and in proper timing with operation of the clamping jaw and whereby the latter is operated to grip the fabric at two points slightly in advance of the cutting operation and to release the same immediately upon the completion of the said cutting operation.

By means of the foregoing description of the trimmer mechanism comprising my invention, it will be noted that the operation of the trimmer is effected through the flexible shaft 17, the double cam and connected jaw and cutter arm operated thereby.

Having thus described my invention, what I claim and desire to secure by Letters Patent is:

1. In a trimmer, of the class described, a bracket adapted for attachment to a looping machine including a ring, clamping jaws adapted to be opened and closed to clamp the fabric, a clamping member, said ring and clamping member being positioned in spaced relation to the jaws and adapted to grip and hold the fabric simultaneously with the gripping of it by the clamping jaws, and a knife positioned to cut the fabric between the two said gripping points.

2. In a trimmer, a bracket adapted for attachment to a looping machine including a

ring carrying impaling pins, guides for directing the fabric through the trimmer, clamping jaws in the path of the movement of the fabric, a yieldable clamp carried by one of the jaws and adapted to co-act with the ⁵ ring to also clamp the fabric, and a cutter positioned for operation beneath the jaws.

3. In a trimmer, a bracket adapted for attachment to a looping machine including a rotatable ring carrying a series of fabric supporting pins, a fixed and a movable clamping jaw located slightly above the surface of the ring for clamping the fabric, a clamping member adjustably mounted upon the movable clamping jaw and adapted to operate against the peripheral surface of the ring in a manner to clamp fabric therebetween, a cutter positioned to operate between the jaws and surface of the ring to shear the fabric ¹⁵ when held by said jaws and clamping member. ²⁰

4. In a trimmer, a bracket adapted for attachment to a looping machine, guides for directing the fabric through the trimmer, clamping jaws in the path of movement of the fabric, a reciprocatory cutter positioned beneath the jaws, and means for operating both the jaws and cutter to hold and cut the fabric, an adjustable clamp attached to one of the ²⁵ jaws and in spaced relation thereto. ³⁰

5. In a trimmer, a bracket adapted for attachment to a looping machine, guides for directing the fabric through the trimmer, one of the said guides being provided with an outwardly projected adjustable extension on its rear end portion to direct the fabric off of the trimmer, a pair of clamping jaws in the path of movement of the fabric, means yieldably mounting one of said jaws, means for intermittently operating the second jaw to clamp and release the fabric, and a cutter positioned beneath the jaws, and adapted to operate in conjunction with the jaws to cut the fabric when held therein. ³⁵

Signed at Bridgeport, in the county of Fairfield and State of Connecticut this 18th day of April, A. D. 1928.

SATTERLEE T. ARNOLD.
